UNITED STATES PATENT OFFICE

HARRY C. BUFFINGTON, OF SPRINGFIELD, ILLINOIS, ASSIGNOR TO THE BAKER MANUFACTURING COMPANY, OF SPRINGFIELD, ILLINOIS, A CORPORATION OF ILLINOIS

SCRAPER OR GRADER

Application filed March 21, 1931. Serial No. 524,344.

My invention relates to new and useful improvements in scrapers or graders and more particularly to a back filler of plow, and so far as there is common subject matter is a continuation of my application filed January 12, 1929, Serial No. 332,038.

The principal object of the present invention resides in the provision of a device of the character described in which the back filler or plow is connected to a tractor, preferably of the crawler type, in such a manner that it may be raised or lowered to inoperative or operative position without placing a side strain on the track frame of the tractor.

A further object of the invention resides in the provision of means connected to the back filler or plow frame and positioned and adapted to engage the track frame in such a manner that when operated in one direction the filler or plow will be raised to inoperative position and when operated in the opposite direction will be lowered to operative position.

Still another object of the invention consists in connecting to the frame of the back filler or plow a bell crank lever, one portion of which will engage the track frame of the tractor, and means being carried on the back filler or plow frame and controlled by the operator of the tractor for operating the bell crank lever.

Another object of the invention resides in the provision of novel means secured to the side beams of the back filler or plow frame to eliminate twist or strain on these beams.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:—

Fig. 1 is a side elevation.
Fig. 2 is a top plan.

Fig. 3 is a transverse vertical section through one of the side beams of the back filler or plow frame and one of the track frames with the bell crank lever shown in rear elevation connected to the side beam.

55

Fig. 4 shows a transverse section through the supporting shaft for the bell crank lever with the bell crank lever and a portion of the track frame shown in side elevation.

Fig. 5 is a longitudinal vertical section through the bearing formed in the side beam of the back filler or plow frame for the bell crank lever supporting shaft, the shaft being shown in side elevation.

Fig. 6 is an end view of the bearing shown in Fig. 5 with the outer plate removed.

Fig. 7 is a side elevation of a slightly modified form of my invention.

Fig. 8 is a top plan of the construction shown in Fig. 7.

70

Fig. 9 is a perspective of the back filler or plow of Figs. 6 and 7 removed from the tractor.

Fig. 10 is a fragmental perspective showing one of the side beams of the back filler or plow frame with a bell crank lever and hydraulic jack for operating the same in position.

Fig. 11 is a fragmental longitudinal section through one of the side beams of the back filler or plow frame and the cylinder of one of the hydraulic operating jacks with parts shown in side elevation.

Fig. 12 is a section on the line 12—12 of Fig. 11 looking in the direction of the arrows; and

Fig. 13 is a section on the line 13—13 of Fig. 11 looking in the direction of the arrows.

In the drawings 1 indicates a tractor of the crawler type including a rear axle 2 and a front axle 3 which support, at opposite sides of the tractor, track frames 4, of the construction shown more particularly in Fig. 3 of the drawings, at opposite ends of which, are mounted the wheels 5 and 6 around which operate the endless tracks 7 of usual construction. The sprocket wheels 5 are driven from any suitable source of power and as the same forms no part of the present invention a de-

90

95

100

tail illustration or description thereof has not been made. Secured to the upper surface of each of the track frames 4, intermediate the ends thereof and centrally of the width is a plate 8 for a purpose which will be later described.

In that form of my improved back filler or plow illustrated in Figs. 1 to 6 of the drawings a frame is connected to and operated by the tractor, this frame consisting of the side beams 9, the rear cross beam 10 and the front cross beam 11 to which the blade 12 is secured. Secured to the bottom surface of each of the side beams 9, to the rear of the blade 12, is a runner 13 and when the frame and blade are in lowered or operative position these runners engage the ground as shown more particularly in Fig. 1 of the drawings. Formed on or secured to the rear end of the tractor are the lugs 14 and formed on or secured to the rear cross beam 10 of the frame of the back filler or plow are the lugs or projections 15 extending inwardly of the cross beam and adapted to be aligned with the lugs or projections 14, as shown more particularly in Fig. 2 of the drawings. Each of the lugs or projections 14 and 15 are provided with aligned openings through which a bolt 16 passes for pivotally connecting the rear end of the frame of the back filler or plow to the tractor. Also extending inwardly from the cross beam 10, adjacent the inner surfaces of each of the side beams 9, is a lug or projection 17 to which is pivotally connected one end of a link or bar 18, the opposite end of the link or bar being pivotally connected to a projection formed on or secured to the rear axle 2 as shown more particularly at 19 in Fig. 2 of the drawings.

Secured to and extending upwardly from each of the side beams 9 is a substantially vertically extending channel or standard 20 the upper ends of which are connected by the tie bar 21. A brace bar 22 is positioned between each of the channels or standards 20 and its supporting beam 9, one end of the brace being secured to the channel or standard while the opposite end is connected to the beam. The channels or standards with the connecting tie bar form a brace to eliminate any twist on the side beams of the back filler or plow frame.

Each of the side beams 9 of the back filler or plow frame is provided intermediate its ends with a thickened or enlarged portion 23 through which is a transversely extending bore 24 forming a housing for the roller bearings indicated generally at 25 which support the shaft 26 having the inwardly projecting portion 27 for a purpose to be later described. The ends of the bore 25 are closed by the plates 28 and 29 which are secured in position by means of the bolts 30 extending through the plates and the thickened and

enlarged portion 23 as shown more particularly in Figs. 5 and 6 of the drawings. It will be understood that a shaft 26 is carried by each of the side beams 9 and the extensions 27 thereof project inwardly towards the track frames 4 as shown more particularly in Figs. 2 and 3 of the drawings. Each of the shafts 26 has an enlargement 31 positioned between the roller bearings 25 as shown more particularly in Figs. 5 of the drawings and this prevents longitudinal movement of the shaft within the bore of the beam.

Keyed to the extension 27 of each of the shafts 26 is a bell crank lever including the collar portion 32 and arms 33 and 34, the arm 34 having a horizontal extension 35 carrying a roller 36 which normally bears upon the plate 8, secured to the adjacent track frame, as shown more particularly in Fig. 3 of the drawings. The roller 36 is secured or held on the horizontal portion 35 of the bell crank lever by means of the pin or key 37. The collar 32 surrounds the extension 27 of the shaft 26 and is held against rotary movement relative thereto by means of the key 38. The collar 32 is split as shown at 39 to provide the lugs 40 through which a bolt 41 extends and receives the nut 42. By adjusting the nut 42 on the bolt 41 the lugs 40 will be drawn toward one another so that the collar 32 will securely grip the extension of the shaft.

Secured to the arm 33 of each of the bell crank levers by means of the pivotal connections 43 and 44 is a rod 45 which extends parallel with the side beam 9 and has secured to its opposite end a sprocket chain 46 operating around a horizontal sprocket 47, as shown more particularly in Fig. 2 of the drawings. After passing around the sprocket wheels 47 the end of each of the chains 46 is secured to a rod 48 extending parallel with the rear beam 10 of the frame and the opposite ends of the rods 48 are connected to the sprocket chains 49 which operate around pulleys 50 and extend upwardly with their ends connected to links 51 as shown more particularly in Fig. 1 of the drawings. The upper ends of the links are secured to a cross head 52 secured to the piston of a hydraulic jack 53. At 54 I have illustrated an oil tank for containing the oil to operate the hydraulic jack and leading from this tank, to a valve 55 is a hose 56. Leading from the valve 55 to the hydraulic jack is a hose 57 and at 58 I have illustrated a control lever, within easy reach of the operator of the tractor, for operating the valve 55 through means of the connecting link or rod 59.

From the above detail description it is thought that the construction and operation of that form of my invention illustrated in Figs. 1 to 6 inclusive of the drawings will be clearly understood. It will be noted

that I have provided a frame which surrounds the tractor and is pivotally connected thereto so that it may be raised and lowered at the will of the operator to position the scraper blade 12 in either operative or inoperative position. Each of the side beams of the frame carries a bell crank lever which has a horizontally extending portion projecting over the upper surface of an adjacent track frame with a roller carried by the horizontal arm in engagement with the upper surface of the track frame or a bearing plate carried thereby. The bell crank levers being carried by the side beams of the back filler or plow frame, and engaging the track frames of the tractor will act to raise and lower the back filler or plow frame according to the direction of operation, the engagement of the roller on the horizontal arm of the bell crank lever with the track frame acting as a fulcrum. In Fig. 1 of the drawings the back filler or plow frame is shown with its forward end lowered and the scraper blade 12 in operative position. When it is desired to raise the blade the operator manipulates the lever 58 to position the valve 55 to allow oil to pass from the tank 54 through the tubes 56 and 57 to the cylinder of the hydraulic jack 53. The entrance of the oil into the cylinder of the jack forces the piston of the jack upwardly and through means of the cross head 52 and links 51 the chains 49 are drawn upwardly to pull upon the rods 48 which in turn operate the sprocket chains 46 to pull the rods 45 and draw the arms 33 of the bell crank levers rearwardly. This movement of the bell crank levers causes the rollers 36 to act as fulcrums in engaging the plates 8 of the track frames 4 and cause the back filler or plow frame to be raised, it being understood that the shafts 26 will rotate within the bores or openings of the side beams 9 while the bell crank levers are keyed to the shafts. The back filler or plow frame will be held in its raised position until the valve 55 is operated to release the oil from within the cylinder of the hydraulic jack and when this is done the weight of the forward end of the frame will cause the parts, including the bell crank levers, to be returned to their normal position. Preferably a pump will be employed for controlling the movement of the oil through the valve 55 but as this pump forms no part of the present invention a detail illustration or description thereof has not been made. I wish to lay particular stress on the fact that the rollers 38 carried by the bell crank levers engage the upper surface of the track frames at the longitudinal center lines of the track frames. By engaging the track frames at these points all side strain on the track frames is eliminated. If the contact was not at the center line there would necessarily be a strain on the track frame.

In Figs. 7 to 13 of the drawings I have illustrated a somewhat different form of my invention in which the back filler or plow frame does not extend entirely around the tractor and in which a hydraulic jack is supported by each of the side or push beams of the frame and connected directly to an arm of the bell crank levers. In this form of the invention the tractor is shown at 60 and includes the rear axle 61 and front axle 62 which support, at opposite sides of the tractor, a track frame 63, at opposite ends of which are mounted the wheels 64 and 65 around which operate the endless tracks 66. The wheel 64 will be driven in any suitable manner to in turn operate the tracks 66. The back filler or plow illustrated in Figs. 7 to 13 inclusive includes a frame consisting of the side or push beams 67 and the front cross beam 68 to which the blade 69 is secured. Secured to each of the side or push beams 67, in the rear of the blade 69, is a runner 70, these runners engaging the surface over which the tractor operates when the frame and blade are in operative position as shown more particularly in Fig. 7 of the drawings. Secured to and extending upwardly from each of the side or push beams 67 is a standard 71, a tie bar or rod 72 connecting these standards at the upper ends as shown more particularly in Fig. 9. Secured to each of the standards and to the side beams is a pair of plates 73 spaced apart as shown more particularly in Figs. 9, 10 and 12 of the drawings to form a bearing for the shafts 74 as shown more particularly in Fig. 12. One end of each of the shafts 74 is provided with an inwardly directed extension to which an arm 75 is secured by means of the bolts 76 and nuts 77. Each of the arms 75 has an inwardly directed horizontally extending portion 78 which overlies the track frames 63, as shown more particularly in Fig. 12 of the drawings, and a roller 79 is carried by each of the horizontally extending portions 78 of the arms 75 and engages the upper surface of a bracket 80 secured to the top of the track frame. Connected to each of the shafts 74, between the plates 73 of each pair, is an arm 81 which, as shown, is arranged at an angle 115 relative to the arm 75 and cooperates with the arm 75 to provide a bell crank lever. Mounted on each of the side or push beams 67, and spaced from the shafts 74 are the brackets 82 in each of which is mounted a transversely extending pin or shaft 83 to which is pivotally connected the cylinder 84 of a hydraulic jack. The piston of the hydraulic jack is indicated at 85 and operates within the cylinder 84 as shown more particularly in Fig. 11. An extension 86 is formed on the outer end of the piston and this extension is pivotally connected at 87 to the arm 81 of the bell crank lever. Each of the brackets 82 is provided with an elongated 130

opening 88 and a bolt 89, carrying the nut 90 extends through the opening and through the top of the beam 67 for adjustably or slidably connecting the bracket to the beam. 5 Formed on or secured to each of the beams 67 is an upwardly extending plate or projection 91 having a threaded opening in which a screw 92 is operable, the inner end of the screw engaging the bracket 82 as shown 10 more particularly in Fig. 11 of the drawings and forming means for adjusting the bracket and holding the same in its adjusted position. A lock nut 93 is shown as carried by the screw 92. Secured to the rear end of 15 each of the cylinders 84 of the hydraulic jacks is a threaded nipple 94 to which one end of a tube or hose 95 is secured for a purpose to be later described.

For pivotally connecting the back filler or 20 plow frame to the tractor I provide the brackets 96 of the construction shown more particularly in Figs. 9, 10 and 13 of the drawings. Each of these brackets has a lug or projection 97 which passes through an opening in the end of its associated side beam 67 and is held therein by means of the collar 98 and screw 99. This forms a pivotal connection between the bracket and side beam. The brackets 96 are of the shape shown more 25 particularly in Figs. 9 and 13 to engage the outer sides of the track frames 63 and are secured thereby by means of the nuts and bolts 100 and 101. Each of the brackets 96 is further provided on its inner face with a 30 recess 102 to receive the projecting end of the rear axle 61 to which the track frames are secured.

Supported and carried by the tractor is an oil tank 103 which supplies oil to the hydraulic jacks. The oil is conveyed to and from the tank 103 through means of the pipe 104, the lower end of the pipe leading and connected to a valve casing 105. Leading from the valve casing 105 are the pipes 106 40 to which the hose or tubes 95 are connected. The valve, not shown, within the valve casing 105 will be operated through means of the lever 107, within easy reach of the operator of the tractor, connected to the valve by 45 means of the rod or bar 108. Preferably a pump, not illustrated, will be provided for controlling the passage of the oil to or from the tank 103 and through the valve within the valve casing 105. It will be understood that 50 the hose or tubes 95 form a flexible connection between the hydraulic jacks and the pipes connected to the valve casing to allow for relative movement of the track frame and other parts when passing over uneven 55 ground. A casing or housing 109 is preferably provided, as shown more particularly in Figs. 7 and 8 of the drawings for enclosing the hydraulic jacks. At 110 and 111 I have indicated wear plates secured to the side or 60 thrust beams 67 and the track frames 63 re-

spectively, to take the side thrust of the back filler or plow frame.

From the above detail description it is thought that the form of my invention disclosed more particularly in Figs. 7 to 13 inclusive of the drawings will be clearly understood. In this form of my invention a hydraulic jack is mounted on each of the side or push beams 67 and the pistons of the hydraulic jacks are connected directly to one of the arms of the bell crank levers. The rollers 79 carried by the bell crank levers engage the upper surfaces of the brackets 80 on the center line of the track frames and this eliminates any side strain on the track frames 80 from the weight of the back filler or plow frame. The standards 71 and connecting tie bar 72 act as a brace to eliminate any twist or strain on the side or push beams of the back filler or plow frame. When the bell crank 85 levers are operated the back filler or plow frame will be raised or lowered, according to the direction of movement of the levers. The engagement of the rollers 79 with the brackets 80 will act as fulcrums. When the back filler 90 or plow frame and blade are in the position shown more particularly in Fig. 7 of the drawings and it is desired to raise the blade the operator will manipulate the lever 107 which will position the valve within the valve 95 casing 105 to permit oil to pass from the tank 103 through the pipe 104, valve casing 105, pipes 106 and hose or tubes 95 to the cylinders 84 of the hydraulic jacks. The oil entering the cylinders will force the pistons 85 outwardly and this movement of the pistons will cause the arms 81 of the bell crank levers to be pushed forwardly and raise the back filler or plow frame and blade carried thereby, it being understood that the rollers 79 engaging the brackets 80 will act as a fulcrum. The frame may be held in its raised position as long as desired and when it is desired to lower the same the operator manipulates the lever 107 to so position the valve in the casing 105 as to allow the oil to pass from the cylinders 84 back into the tank 103.

In that form of the invention shown in Figs. 7 to 13 the hydraulic jacks at opposite sides may be operated together or separately thus enabling the operator to raise or lower one side at a time, if desired. It might be necessary at sometime, when operating, one side is overloaded and through the fact that either one of the cylinders can be operated separately, the overloaded side could have more pressure applied to that side. The weight of the moldboard or forward end of the blade frame is at all times evenly distributed by the two jacks. As the weight of the moldboard or blade frame is being carried on the cylinders through the bell cranks and the uneven ground causes one track to go up and the other to go down it would naturally apply more pressure on the side where the 120

track is going up and through the fact that the jacks are directly connected to the pipe 106 from one side to the other causes the two jacks to always be equalized in pressure. It 5 will be further understood that the valve controlled by the lever 107 may be positioned, when desired, for operating both jacks in unison or one jack at a time.

Having fully described my invention what 10 I claim as new and desire to secure by Letters Patent is:—

1. A scraper of the character described including in combination with a tractor having a track frame, a blade carrying frame 15 pivotally connected to the tractor, a member carried by the blade carrying frame and engaging the track frame, and means for operating the member to raise and lower the blade carrying frame.

20 2. A scraper of the character described including in combination with a tractor having a track frame, a blade carrying frame pivotally connected to the tractor, a member pivotally connected to the blade carrying 25 frame and engaging the track frame, and means for operating said member to raise and lower the blade carrying frame.

3. A scraper of the character described including in combination with a tractor having a track frame, a blade carrying frame 30 pivotally connected to the tractor, a member carried by the blade carrying frame and engaging the track frame at approximately the longitudinal center line thereof, and 35 means for operating the member to raise and lower the blade carrying frame.

4. A scraper of the character described including in combination with a tractor having a track frame, a blade carrying frame 40 pivotally connected to the tractor, a member pivotally connected to the blade carrying frame and having a portion engageable with the track frame at approximately the longitudinal center thereof, and means carried 45 by the blade carrying frame for operating the member to raise and lower the blade carrying frame.

5. A scraper of the character described including in combination with a tractor having 50 a track frame, a blade carrying frame pivotally connected to the tractor, a bell crank lever pivotally connected to and carried by the blade carrying frame, one arm of said lever overlying and engaging the track 55 frame, and means connected to the opposite arm of the bell crank lever for operating the same to raise and lower the blade carrying frame.

6. A scraper of the character described 60 including in combination with a tractor having a track frame, a blade carrying frame pivotally connected to the tractor, a bell crank lever pivotally connected to and carried by the blade carrying frame, one arm of 65 said lever overlying and engaging the track

frame at approximately the longitudinal center thereof, and means connected to the opposite arm of the bell crank lever for operating the same to raise and lower the blade carrying frame.

7. A scraper of the character described including in combination with a tractor having a track frame, a blade carrying frame pivotally connected to the tractor, a bell crank lever pivotally connected to and carried by the blade carrying frame, one arm of the bell crank lever overlying the track frame, a roller carried by the overlying arm and engageable with the track frame, and means connected to the opposite arm of the bell crank lever for operating the same to raise and lower the blade carrying frame.

8. A scraper of the character described including in combination with a tractor having a track frame, a blade carrying frame 85 pivotally connected to the tractor, a bell crank lever pivotally connected to and carried by the blade carrying frame, one arm of the bell crank lever overlying the track frame, a roller carried by the overlying arm 90 and engageable with the track frame at approximately the longitudinal center thereof, and means connected to the opposite arm of the bell crank lever for operating the same to raise and lower the blade carrying frame.

9. A scraper of the character described including in combination with a tractor having track frames, a blade carrying frame surrounding the tractor, and pivotally connected thereto, said blade carrying frame including 100 side beams and end beams, a member carried by each of the side beams of the blade carrying frame and engageable with the track frames, and means carried by one of the end beams of the blade carrying frame and connected to the members carried by the side beams thereof for operating the members to raise and lower the blade carrying frame.

10. A scraper of the character described including in combination with a tractor having track frames, a blade carrying frame surrounding the tractor and pivotally connected thereto, said blade carrying frame including side beams and end beams, a bell crank lever pivotally connected to each of the side beams 115 and having a portion overlying and engaging the adjacent track frame, and means carried by one of the end beams of the blade carrying frame and connected to the bell crank levers for operating the same to raise and lower the 120 blade carrying frame.

11. A scraper of the character described including in combination with a tractor having track frames, a bearing plate secured to each of the track frames, a blade carrying 125 frame surrounding the tractor and pivotally connected thereto, said blade carrying frame including side beams and end beams, a bell crank lever pivotally connected to each of the side beams of the blade carrying frame and 130

having a portion overlying and engaging the bearing plate of the adjacent track frame at approximately the longitudinal center of the track frame, and means carried by one of the 5 end beams of the blade carrying frame and connected to the bell crank levers for operating the same to raise and lower the blade carrying frame.

12. A scraper of the character described 10 including in combination with a tractor having track frames, a blade carrying frame pivotally connected to the tractor, members carried by the blade carrying frame and engageable with the track frames, and hydraulic 15 means connected to said members for operating the same to raise and lower the blade carrying frame.

13. A scraper of the character described 20 including in combination with a tractor having track frames, a blade carrying frame pivotally connected to the tractor, members carried by the blade carrying frame and engaging the track frames, and hydraulic means carried by the blade carrying frame and connected to the members for raising and lowering 25 the blade carrying frame.

14. A scraper of the character described including in combination with a tractor having 30 a track frame, a blade carrying frame pivotally connected to the tractor, a bell crank lever pivotally connected to the blade carrying frame and having one arm overlying and engaging the track frame, and a hydraulic jack mounted on the blade carrying frame and 35 connected to the other arm of the bell crank lever for operating the same to raise and lower the blade carrying frame.

15. A scraper of the character described 40 including in combination with a tractor having a track frame, a blade carrying frame pivotally connected to the tractor, a bell crank lever pivotally connected to the blade carrying frame and having one arm overlying and engaging the track frame, a hydraulic jack 45 mounted on the blade carrying frame and connected to the other arm of the bell crank lever for operating the same to raise and lower the blade carrying frame, and means for adjusting the hydraulic jack.

50 16. A scraper of the character described including in combination with a tractor having a track frame, a blade carrying frame pivotally connected to the tractor, a bell crank lever pivotally connected to the blade carrying frame and having one arm overlying and engaging the track frame, and a hydraulic jack mounted on the blade carrying frame and adapted for operating the bell crank lever to raise and lower the blade carrying 55 frame, said hydraulic jack including a cylinder pivotally connected to the blade carrying frame and a piston operable in the cylinder and connected to an arm of the bell crank lever.

60 17. A scraper of the character described in-

cluding in combination with a tractor having track frames, a blade carrying frame including side beams pivotally connected to the tractor, a bell crank lever pivotally connected to each of the side beams of the blade carrying frame and having one arm overlying and engaging the adjacent track frame, and a hydraulic jack mounted on each of the side beams of the blade carrying frame and connected to the other arm of the bell crank lever for operating the bell crank lever to raise and lower the blade carrying frame. 70

18. A scraper of the character described including in combination with a tractor having a track frame, a bracket mounted on the track frame, a blade carrying frame pivotally connected to the tractor, a member carried by the blade carrying frame and engageable with the bracket secured to the track frame, and means for operating said member to 80 raise and lower the blade carrying frame. 85

19. A scraper of the character described including in combination with a tractor having a track frame, a bracket secured to the track frame, a blade carrying frame pivotally connected to the tractor, a bell crank lever pivotally connected to the blade carrying frame and having an arm overlying the bracket secured to the track frame, a roller carried by said overlying arm and engageable with the bracket, and means connected to the other arm of the bell crank lever for operating the same to raise and lower the blade carrying frame. 90

20. A scraper of the character described 100 including in combination with a tractor having a track frame, a bracket secured to the track frame, a blade carrying frame pivotally connected to the tractor, a bell crank lever pivotally connected to the blade carrying frame and having an arm overlying the bracket secured to the track frame, a roller carried by said overlying arm and engageable with the bracket at approximately the longitudinal center of the track frame, and means connected to the other arm of the bell crank lever for operating the same to raise and lower the blade carrying frame. 105

21. A scraper of the character described 110 including in combination with a tractor having a track frame, a blade carrying frame including side beams pivotally connected to the tractor, a bell crank lever pivotally connected to each of the side beams of the blade carrying frame and having one arm overlying and engaging the adjacent track frame, a hydraulic jack mounted on each of the side beams of the blade carrying frame and connected to the other arms of the bell crank levers for operating the bell crank levers to raise and lower the blade carrying frame, and means for controlling the operation of the hydraulic jacks. 115

22. A scraper of the character described 120 including in combination with a tractor hav-

ing a track frame, a blade carrying frame connected to the tractor, a member carried by the blade carrying frame and engaging the track frame, and means for operating the member to raise and lower the blade carrying frame.

In testimony whereof I hereunto affix my signature.

HARRY C. BUFFINGTON.
